PERFORATING AND FORMING APPARATUS

Albert Mutschler, Rochester, N. Y., assignor to
A. & H. G. Mutschler Inc., Rochester, N. Y.

Application November 4, 1929, Serial No. 404,685

1 Claim. (Cl. 164—91)

This invention relates to a perforating and forming apparatus and has for its various objects:

To provide an apparatus with which a plurality of dies and punches are operated to simultaneously produce a plurality of forming or perforating operations on a single piece of work.

To provide an apparatus with which a series of perforating or forming operations may be performed without the aid of the customary punch press used for such operations.

To produce an apparatus with which a perforating or forming operation can be performed in full sight of the operator and in a position in which the stock to be perforated or formed can be most conveniently and efficiently fed to the apparatus.

To produce an apparatus for perforating or forming operations which is so constructed that the stock to be perforated or formed can be fed to and withdrawn from the apparatus without danger to the operator of the apparatus.

These and other objects of this invention will be apparent from the drawings, the specification and the appended claim forming a part thereof.

In the accompanying drawings:

Figure 1 is a front elevation of the apparatus and the driving mechanism therefor.

Figure 2 is an end elevation of the apparatus and the driving mechanism for it.

Figure 3 is an enlarged detail plan view of the apparatus with a portion of it broken away to illustrate part of the mechanism thereof.

Figure 4 is an enlarged detail section view of the apparatus, the section being taken on the line 4—4 of Figure 3.

In the several figures of the drawings like reference numerals indicate like parts.

The apparatus forming the subject matter of my present invention is illustrated in the drawings in a form in which it is particularly adapted for perforating the wall of sheet metal cups with a plurality of holes. This of course is only one use for which this particular apparatus can be employed and many other uses will suggest themselves to those skilled in the art. I therefore do not want to limit myself to the particular use for the apparatus that is illustrated in the drawings and described in this specification but wish to have it understood that the apparatus with slight modifications and adjustments, which can be made by any one skilled in the art, is equally adaptable for other perforating and forming operations.

As illustrated in the figures the apparatus is

preferably mounted on a suitable angle bracket 1 which supports it in a position in which the stock to be perforated can be conveniently fed thereto by the operator as will hereinafter be described. The angle bracket in turn is mounted on a suitable bed plate 2 and above it or below it may be mounted the crank shaft 3 by which the apparatus is actuated. The crank pin 4 of the crank shaft is connected with the operating arm 20 of the apparatus by means of the connecting rod 5 and the universal link 6 in order to give the operating arm 20 an oscillating motion on the rotation of the crank shaft 3. The crank shaft may be intermittently or continuously operated in any suitable manner and suitable means may be provided with which the rotation of the shaft can be controlled by the operator in order to operate the apparatus at will.

The apparatus proper comprises a bed plate 7 which is cut away to provide a bearing for the ring member 8. The top of the bed plate is conically recessed with a series of uniformly spaced radial grooves 9, 9 provided in the recess. In the center of the conical recess is provided a cylindrical pocket 10 and in this pocket is mounted the die 10A. The punches which cooperate with this die are indicated by reference numerals 10B, 10B and are provided on the ends of the shanks 11, 11 which are mounted to slide and reciprocate in the radial grooves 9, 9. A link 12 is pivoted to the outer end of each of the shanks 11 and this link in turn is pivoted to a second link 13 which with its outer end is pivoted to the under side of the conically recessed cover plate 14. The links 12 and 13 thus form a toggle with which the shanks 11 are connected to the stationary cover plate 14. The cover plate extends over the bed plate 7 and covers the radial slots 9, 9 to hold the shanks 11, 11 in place therein. The cover plate is fastened to the bed plate by means of the screws 15, 15 which pass thru the cover plate and are threaded into the conically recessed portion of the bed plate at points between the radial slots 9, 9. The cover plate is thus fixed with the bed plate and provides a fixed anchorage to which the outer end of the toggle is pivoted.

On the ring member 8 are mounted in pairs a series of studs or rollers 16 and 17 which are located so as to project upwardly from the ring member on each side of the center of the toggle formed by the links 12 and 13. On the oscillation of the ring member on the bed plate the studs or rollers 16 and 17 operate to straighten and bend the toggles and in doing so move the shanks 11 back and forth in the radial slots in the bed plate

7. The ring member 8 is oscillated by the segmental pinion 18 which meshes with the segmental gear 19 formed in the perimeter of the ring member 8. The segmental pinion 18 is provided 5 with an arm 20 to the outer end of which is pivoted the universal link 6.

As above described the universal link 6 and connecting rod 5 are reciprocated by the crank pin 4 of the crank shaft 3. The rotation of the crank 10 shaft thus causes the segmental pinion 18 to oscillate which in turn oscillates the ring member 8 to reciprocate the shanks 11, 11 in the radial slots in the bed plate 7. The die 10A located in the center of the bed plate 7 is provided with a hole 15 for each of the punches 10B so that as these punches are reciprocated by the shanks 11 they enter the die holes in the die. The metal cut 25 which is placed over the die is thus perforated with a plurality of holes at each oscillation of the 20 ring member caused by one revolution of the crank shaft 3.

As illustrated in Figures 1 and 2 the angle bracket 1 supports the apparatus in an angular position which is most convenient for the operator to feed the material into the center of the 25 apparatus. In this way the operator can sit or

stand in front of the apparatus and place a piece of material on the die in the center of the cover plate to have the apparatus perforate it and then withdraw the material from it without having to reach very far or place his fingers in jeopardy between the punch and the die. 80

I claim:

In a perforating and forming apparatus the combination of a cylindrical base, a ring member mounted to oscillate on said cylindrical base, said cylindrical base having a central pocket in the top thereof with radial channels leading from said pocket, a cover plate having a central opening therein located on top of said base to cover said radial channels without covering said central pocket, plungers mounted to slide in said radial channels and held in place therein by said cover plate, a toggle for each of said plungers and connected to one end of each of said plungers and with the other end to said cover plate, studs carried by said ring member and engaging each side of said toggle to operate said toggle on the oscillation of said ring member, and means for oscillating said ring member. 95
